HOBBY HORSE

Harold A. Mortensen, 10636 Myers Way, Seattle, Wash.
Filed Mar. 16, 1961, Ser. No. 96,161
4 Claims. (Cl. 280—1.13)

This invention relates to a children's amusement apparatus and more particularly to a mobile hobby horse.

The general object of my invention is to provide a mobile hobby horse which has resilient mounting feet.

A more particular object is to provide a hobby horse which can closely simulate both the galloping motion and bucking movements of an actual horse.

A further particular object is to provide a relatively safe mobile hobby horse with no sharp corners or edges to harm a child.

Yet another specific object is to provide a mobile horse which will not scuff the floor or damage the walls of a room in which the hobby horse is being used. These together with other more particular objects and advantages will appear and be understood in the course of the following description and claims, the invention consisting in the novel construction and in the adaptation and combination of parts hereinafter described and claimed.

In the accompanying drawings:

FIGURE 1 is a side elevational view of a hobby horse embodying preferred teachings of my invention.

FIG. 2 is a top plan view thereof.

FIG. 3 is a side elevational view of the mounting means of one embodiment of my invention.

FIG. 4 is a side elevational view of the mounting means of a second embodiment thereof; and

FIG. 5 is a side elevational view of the mounting means of a third embodiment.

Referring to FIG. 1, numeral 10 designates generally a hobby horse having two front legs 11 and right and left hind legs 12 and 13 respectively. The horse is equipped with a saddle 14 to support the rider, and reins 17 and a handle 18 on the upper neck 20 which admit of being selectively grasped by the rider. The hoofs of the front legs are preferably joined to integrate the same in a single member 21. This single member is supported by a front resilient foot 22, and the hind legs 12 and 13 each have attached to their respective hoofs 23 and 24 resilient feet 26 and 27 respectively. The two hind legs desirably reach well to the rear in a "galloping" stretch and the three hoofs 21, 23 and 24 produce a substantial isosceles triangle, an imagined line between the rear feet forming the base thereof. The horse, when at rest on its three ground bearings, places the body of the horse generally level with the supporting floor.

FIG. 3 shows one of the three similar resilient feet 21, 23, and 24, as the case may be, of the first embodiment of my invention. Threaded into a socket 31 firmly fixed in a hoof of the horse is one end of a stud screw 32 which has its opposite end threaded into a foot socket 33. The socket 33 is formed in a piece 29 vulcanized in the neck 30 of an inflatable ball-forming balloon 34. It will be understood that the lower portion 37 of the ball is the only portion thereof which makes contact with the floor and that of said contact portion has considerable resiliency with respect to the mounting portion. For inflating the ball, the ball is formed in a wall portion thereof with an opening 38 which accommodates the insert needle (not shown) of a conventional athletic pump. Lips 39 prolonged inwardly act by air pressure within the ball to

2

normally seal the opening. The ball is composed of a plastic or rubber material which will not scuff or abrade a floor or wall.

The second embodiment of a foot shown in FIG. 4 is designated generally by 40. As in FIG. 2 there is the hoof socket 31 with the mating stud 32 and the foot socket 33 formed in the socket-piece 29. Extending down from the foot socket is a resilient spring 44 generally shaped as an inverted question mark. The upper or straight portion 46 of the spring performs the function of a mounting stem and is attached to the foot socket. The lower or curved shoulder portion 47 contacts the floor. The spring is coated with a plastic or rubber sheathing to prevent scuffing or abrasion of the walls or floor.

In the third embodiment of FIG. 5, the foot incorporates a ball 50 quite similar to that of the first embodiment and augments compressed air pressure within the ball of a helical compression spring 58 invested by the ball. This spring is attached at its upper end to the foot socket 53, with its lower end engaging the bottom wall of the ball 54, being stepped upon a pad 60 which reinforces the bottom wall. In this embodiment the air pressure within the ball need not be high and could be readily supplied by mouth, using a suitable removable fitting for this purpose.

In operation the rider mounts the horse and rocks the horse forward and backward by his own body motion. With moderate rocking the horse will oscillate back and forth in the same place. With more forceful body movements of the rider the horse can be made to move along the floor, forwardly, rearwardly and laterally, and can be guided with considerable accuracy through skilled control.

It is believed that the invention will have been clearly understood from the foregoing detailed description of my now preferred embodiments. Changes in the details of construction will suggest themselves and it is accordingly my intention that no limitations be implied and that the hereto annexed claims be given the broadest interpretation to which the employed language fairly admits.

What I claim is:

1. A hobby horse having front and back legs, only a single resilient support being connected to both said front legs, two resilient supports each being connected to a respective one of said back legs, each of said supports having a mounting portion which is secured to its respective leg, each support also having a contact portion to contact a floor, the contact portion being resiliently connected to its mounting portion, said supports being secured to the legs of the hobby horse only through their respective mounting portions.

2. The device as recited in claim 1, each of said supports being a resilient inflatable ball.

3. The device as recited in claim 1 each of said supports being a leaf spring with a protective coating over the bottom portion of the leaf spring.

4. The device as recited in claim 1, each of said support means being a resilient spring enclosed in an inflatable ball.
